J. A. STEINMETZ

MOORING DIRIGIBLE AIRCRAFT

Filed Dec. 29, 1925

Patented July 5, 1927.

1,634,964

UNITED STATES PATENT OFFICE.

JOSEPH A. STEINMETZ, OF PHILADELPHIA, PENNSYLVANIA.

MOORING DIRIGIBLE AIRCRAFT.

Application filed December 29, 1925. Serial No. 78,107.

My invention relates to the mooring of dirigible balloons, and particularly to a method of bringing one to a safe anchorage after a flight.

5 In the accompanying drawings which are merely illustrative:—

Figure 1 shows a dirigible balloon attached to a mooring line from a mooring mast.

10 In Figure 2 the mooring mast is omitted.

Figure 3 shows an automatic clutch as seen from above.

Figure 4 is a section on the line 4—4 of Figure 3.

15 Figure 5 is a view from above of the mooring line engaging arms and clutch.

In these figures 10 represents a captive balloon, 11 a mooring line attached thereto, 12 a mooring mast and 13 a winch upon 20 which the mooring line may be wound.

A dirigible balloon 14 carries at its forward end the spreading cable engaging arms 15 which extend forwardly and spread laterally in a V shape to pick up the mooring line 11 and guide it into a suitable automatic clutch. The clutch illustrated has one pivoted cam member 16 which is forwardly tapered and may have an extension 16' to prevent rotation beyond an operative position and a handle 18 for optional manual operation. Opposite the cam member 16 is a rigid tapered abutment 17.

In Figure 2 are shown the usual drag ropes 19 and a swiveled sheave block 20 35 which serves to guide the line to the winch 13, which is preferably operated by a motor, not shown.

The present method of mooring a dirigible balloon is to steer it in the direction of 40 a station, lower it by partially deflating the balloon, throw out drag ropes which are grasped by large numbers of waiting men who draw the balloon to a mooring anchor, a mast, or hangar shelter. When the balloon is to be anchored to a mooring mast of a "mother ship" men in small boats are substituted for the men on land and these boats tow the dirigible balloon to her anchorage.

Under ideal conditions this is a difficult 50 slow and hazardous proceeding. Owing to the lightening of the balloon through the reduction in the fuel load, or the expansion of the gases within the same due to a rise in temperature, the airship tends to rise and 55 it is usual to reduce this excess buoyancy by opening gas valves. This involves the

loss of valuable gas and deprives the ship of the power to immediately resume its flight, or even to rise quickly above buildings or other obstructions to aerial navigation.

60 After a flight, even a mild wind may make the mooring of a dirigible by the common methods very difficult, and a low fog may entirely obscure all landmarks from the dirigible.

65 My method of mooring requires the use of very simple devices, which obviously may be modified as required by special conditions.

In the form shown in Figure 2 the dirigible is shown as having engaged the mooring 70 line 11 and the drag ropes 19 have been lowered. The motion of the dirigible after the mooring line has been forced between the jaws of the automatic clutch illustrated in Figure 4 draws the line taught as the cam 75 member 16 grips the line.

The winch 13 serves to draw the dirigible downwards until the drag lines reach the ground when the waiting crew can make the ship fast or move it into a hangar. Should 80 the buoyancy of the dirigible tend to raise the free end while being moored, ballast may be shifted to overcome this tilting. The drag lines may be used to take on additional ballast before releasing the dirigible from 85 the mooring line. The automatic clutch is adapted to release the line 11 when the latter is slackened by the winch and the dirigible is backed away.

The captive balloon 11 will carry suitable light signals and if desired may also 90 carry a balloonist as an observer. This captive balloon may be floated above the level of ground fogs and thus serves as a light-house to guide a dirigible to a desired mooring and is an aid to navigation.

95 What I claim is:

1. The method of mooring aircraft which consists in lifting a mooring line by a captive aircraft to an elevation at which a dirigible may be safely navigated, and clutching a dirigible aircraft to said cable by devices carried by said dirigible aircraft.

100 2. The method of mooring dirigible aircraft which consists in carrying aloft the free end of an anchored cable by a captive balloon, navigating a dirigible aircraft to engage and clutch said cable by devices carried by said aircraft and drawing said dirigible aircraft to a desired anchorage by force applied to said cable.

105 3. The method of mooring a dirigible bal-

2
loon which consists in navigating said balloon to the anchoring cable of a captive balloon, attaching said balloon to the cable by means of clutching devices on said dirigible balloon and drawing it downwards by force applied to the cable.

4. The method of mooring a dirigible balloon which consists in elevating a free end of an anchoring cable above the maximum

elevation of ground fogs by a captive balloon carrying suitable identifying signals, clutching said balloon to said cable by automatic devices carried by said balloon, and drawing said balloon to an anchorage by a power operated winch.

In testimony whereof I hereunto affix my signature.

JOSEPH A. STEINMETZ.
